UNITED STATES PATENT OFFICE.

AIKEN C. TAYLOR, OF RICHMOND, VIRGINIA.

ELECTRICAL COMB.

1,197,872.

Specification of Letters Patent. Patented Sept. 12, 1916.

Application filed July 26, 1915. Serial No. 41,980.

To all whom it may concern:

Be it known that I, AIKEN C. TAYLOR, a citizen of the United States, residing at Richmond, in the county of Henrico and State of Virginia, have invented a new and useful Electrical Comb, of which the following is a specification.

This invention relates to improvements in that class of combs adapted to be heated by electricity and especially designed for drying the hair after shampooing.

The principal objects of the invention are to provide a comb so constructed as to facilitate ironing and drying the hair, for which purposes the comb is peculiarly constructed, to adapt it to be readily taken apart, cleaned, and reassembled, and when so assembled to inclose an electrical heater of conventional type and in such manner as to avoid all looseness of the parts.

Other objects and advantages of the invention will hereinafter appear, and the novel features thereof will be particularly pointed out in the claims.

Referring to the drawing: Figure 1 is a side elevation of an electrical comb embodying my invention; Fig. 2 is a horizontal sectional view of the same on the line 2—2 of Fig. 1; Figs. 3 and 4 are similar vertical transverse sectional views of the comb, the latter showing a modified form.

Similar numerals of reference indicate similar parts in all the figures of the drawings.

The comb is constructed of any desired good heat-conducting metal, and comprises a hollow substantially cylindrical body-portion, preferably divided longitudinally to form two sections of semi-cylindrical shape and designated as 1 and 2. The section 1 preferably has its edges provided with longitudinal grooves 3 and 5, the same receiving corresponding ribs 4 and 6 formed on the adjacent edges of the companion section 2. As will be understood, the ribs and grooves interlock, neatly and completely close the joint between the sections and also prevent radial separation of the two sections. At its outer end, the said body-portion is preferably formed with an external annular in-

clined shoulder or boss 22, and at its inner end with a conical-shaped tang 10.

The sections 1 and 2 may have formed at the opposite sides of the vertical radial center of the body-portion, depending and slightly outwardly flared ironing-ribs 8, the two thus extending parallel from end to end of the comb, at each side of the series of teeth 7. The teeth 7 are preferably carried by the section 1, and the ribs extend along the sides of the same may be either plain or corrugated, the idea being to iron the hair as the strands are divided by the teeth of the comb and thus more effectually dry the same. If preferred, the ribs may be omitted (as shown in Fig. 4), and the cylindrical body-portion of the comb be relied upon to iron the hair; the ribs, however, are preferred. If employed, the ribs, as before stated, are best corrugated, such corrugations being indicated as at 9.

The handle 11, may be formed of any suitable material and given any external shape desired. In the present instance it is internally and centrally bored, as at 12, terminates at its outer end in a shallow cylindrical cavity 14, and at its opposite or inner end in a conical cavity 13, the latter receiving the tang 10 of the body-portion of the comb.

Within the hollow body-portion of the comb is located the electrical heater 16, which with the exceptions I am about to enumerate, is of the conventional form. These exceptions consist in an external cap 19 affixed to and extending beyond the usual annular boss 17 usually provided at the front end of the heater, and in having its rear boss 18 made slightly conical. The slightly conical boss 18 abuts against an internal conical shoulder 15, formed within the hollow comb-body immediately in advance of the tang 10, and the cap 19 is formed with an annular peripheral flange 20, the inner face of which is slightly inclined in opposition to the inclined surface of the boss or inclined shoulder 22 of the comb body-portion. From the heater 16 there extends through the tang 10 and the hollow handle 11, a metal tube 23, the same terminating within the cavity 14 at the outer end of the handle. Within the cavity is 100

neatly fitted and seated a nut 25, preferably notched to receive a spanner-wrench, and said nut is threaded upon the tube. The tube serves as a conductor for the electrical conductors 24, which may lead to any source of electrical energy, as for instance, an ordinary electric light socket.

The operation of combing and drying the hair will be readily understood, as such does not differ materially from the operation of other similar devices except as to co-operation of the convoluted or corrugated ironing-flanges with the comb-teeth 7. It will be seen, however, that by first loosening the nut 25, the handle may be withdrawn, whereby the electrical heater may be slightly pushed forward so as to disengage its flange 20 with the boss 22 of the body-portion, and the parts be thus completely separated, cleaned or replaced, the comb being capable of being thoroughly sterilized in any sterilizing liquid without danger of wetting the heater. To replace the parts, the sections are first assembled in position about the heater, the cap 19 engaged over the end of the comb-body, which causes the inclined or conical boss 18 to abut against the inclined shoulder 15. The handle is now slipped forward so that its conical cavity receives the conical tang 10, whereupon the nut 25 is run down upon the thread of the tube 23. It will be evident that by tightening upon the nut 25, the handle and comb will be drawn together, the inclined cavity of the handle serving to bind against the inclined tang 10, so as to draw the sections 1 and 2 together. At the same time a similar operation or drawing of the sections together will occur at the outer end of the comb-body by reason of the inclined flange of the cap 19 riding up the oppositely inclined boss 22 of the comb-body. It will further be seen that the inclined surface of the boss 18 operating against the oppositely inclined surface 15 of the comb-body, will cause the electrical heater to become wedged in position, so that no looseness or rattling can occur as the comb is handled during operation.

Having described my invention, what I claim is:

1. In an electrical comb, the combination with a hollow cylindrical body-portion divided longitudinally into sections, and at its inner end terminating in a cone-shaped tang, of an electrical heater located in the body-portion, at its outer end having a circular cap overlapping the body-portion and at its inner end having a tubular extension, a bored handle located on the tubular extension and at its inner end having a conical cavity receiving the cone-shaped tang, and a nut threaded on the outer end of the tubular extension and binding against the inner end of the handle.

2. In an electrical comb, the combination with a hollow cylindrical body-portion divided longitudinally into sections, at its inner end terminating in a cone-shaped tang and at its outer end provided with an external boss having an inclined surface, of an electrical heater located in the body-portion, at its outer end having a circular flanged cap, the flange being inclined opposite to the boss it embraces, and at its inner end said heater having a tubular extension, a handle bored and mounted on the tubular extension and at its inner end having a conical cavity receiving the conical tang and at its outer end having a cavity, and a nut threaded on the tubular extension within the cavity.

3. In an electrical comb, the combination with a hollow cylindrical body-portion, the same being provided at its outer end with an external annular inclined boss, and at its opposite end with an inclined internal shoulder and beyond the same terminating in a conical-shaped tang, of an electrical heater having front and rear bosses and at its rear end a tubular extension, a cap secured to the front boss and provided with an annular flange having an inclined face overlapping the inclined boss of the body portion and the rear boss inclined opposite to and seated upon the internal shoulder of the body-portion, a handle located on the tubular extension and having at its inner end a cone-shaped cavity receiving the tang of the body-portion and at its opposite end having a shallow annular cavity, and a nut located in the latter cavity and threaded on the end of the tubular extension.

4. In an electrical comb, the combination with a hollow cylindrical body-portion divided longitudinally into sections tongued and grooved together at their edges, said body-portion terminating at its rear end in a cone-shaped tang, of an electrical heater terminating at one end in a cap engaging over the body portion and at its opposite end in a tubular extension, a bored handle mounted on the tubular extension and having at its inner end a conical cavity receiving the tang, and a nut threaded on the outer end of the tubular extension and bearing against the end of the handle.

5. In an electrical comb, the cylindrical body-portion adapted to receive an electrical heater, said body portion being divided longitudinally into sections the edges of which overlap, combined with means for clamping the sections together.

6. An electrical comb, comprising, a cylindrical hollow body-portion adapted to receive an electrical heater, said body-portion having a series of comb-teeth and at the side thereof a longitudinal ironing-flange depending along side the teeth.

7. An electrical comb, comprising, a cylin-

1,197,872

drical hollow body-portion adapted to receive an electrical heater, said body-portion having a series of comb-teeth and at the side thereof a longitudinal ironing-flange depending alongside the teeth and having its edges corrugated.

In testimony whereof I have signed my

name to this specification in the presence of two subscribing witnesses.
